UNITED STATES PATENT OFFICE

WILLIAM F. NEWBERRY, OF MONTCLAIR, NEW JERSEY, ASSIGNOR TO F. W. WOOLWORTH CO., OF NEW YORK, N. Y., A CORPORATION OF NEW YORK

DESIGN FOR AN EGG-BEATER BOWL

Application filed January 15, 1930. Serial No. 34,134. Term of patent 7 years.

To all whom it may concern:

Be it known that I, WILLIAM F. NEWBERRY, a citizen of the United States of America, residing at Montclair, in the county of Essex and State of New Jersey, have invented a new, original, and ornamental Design for Egg-beater Bowls, of which the following is a specification, reference being had to the accompanying drawing, forming part thereof.

Fig. 1 is a side elevation of the eggbeater bowl, showing my design.

Fig. 2 is a bottom view of the eggbeater bowl shown in Fig. 1.

I claim—

The ornamental design for an eggbeater bowl, substantially as shown.

In testimony whereof I hereto affix my signature

WILLIAM F. NEWBERRY.
